(57) **ABSTRACT**

Disclosed herein is an aerosol-generating device (100) for
generating aerosol from an aerosol-generating material. The
aerosol-generating device comprises: a housing (102); and a
heating assembly arranged in the housing for receiving
aerosol-generating material. The heating assembly is con-
figured to heat aerosol-generating material received in the
heating assembly. The housing has a characteristic extent
(130) in a first direction (120) of not more than 85 mm, a
characteristic extent (132) in a second direction (122) per-
pendicular to the first direction of not more than 45 mm, and
a characteristic extent (134) in a third direction (124) per-
pendicular to the first and second directions of not more
than 23 mm.

AEROSOL-GENERATING DEVICE

RELATED APPLICATION INFORMATION

The present application is a National Phase entry of PCT Application No. PCT/EP2020/0562267, filed Mar. 9, 2020, which claims priority from GB Patent Application No. 1903308.3, filed Mar. 11, 2019, each of which is hereby fully incorporated herein by reference.

TECHNICAL FIELD

The present invention relates to an aerosol-generating device, a method of generating an aerosol using the aerosol-generating device, and an aerosol-generating system comprising the aerosol-generating device.

BACKGROUND

Articles such as cigarettes, cigars and the like burn tobacco during use to create tobacco smoke. Attempts have been made to provide alternatives to these types of articles, which burn tobacco, by creating products that release compounds without burning. Apparatus is known that heats smokable material to volatilise at least one component of the smokable material, typically to form an aerosol which can be inhaled, without burning or combusting the smokable material. Such apparatus is sometimes described as a “heat-not-burn” apparatus or a “tobacco heating product” (THP) or “tobacco heating device” or similar. Various different arrangements for volatilising at least one component of the smokable material are known.

The material may be for example tobacco or other non-tobacco products or a combination, such as a blended mix, which may or may not contain nicotine.

SUMMARY

According to a first aspect of the invention there is provided an aerosol-generating device for generating aerosol from an aerosol-generating material. The aerosol-generating device comprises a housing, and a heating assembly arranged in the housing for receiving aerosol-generating material. The heating assembly is configured to heat aerosol-generating material received in the heating assembly.

The housing has a characteristic extent in a first direction of not more than 85 mm, a characteristic extent in a second direction perpendicular to the first direction of not more than 45 mm, and a characteristic extent in a third direction perpendicular to the first and second directions of not more than 23 mm.

In some embodiments, the housing comprises a base which extends along a first plane normal to the first direction. The housing may further comprise a top have arranged opposite to the base.

In one embodiment, the top face extends along a fourth plane, the fourth plane extending along the third direction and forming a dihedral angle with the first plane of 2.5°.

The base and top face may be connected by a body portion. The body portion may comprise a front face, rear face, first side portion, and second side portion, each extending from the base to the top face in the first direction. The front face is arranged opposite the rear face, and the first side portion is arranged opposite the second side portion. In one embodiment, the front face and rear face are connected by the first side portion at a first edge of each face, and by the second side portion at a second edge of each face.

The first side portion and/or the second side portion may be substantially curved. The front face and/or rear face may be substantially planar.

Preferably, the front face, rear face, first side portion and second side portion are each substantially perpendicular to the base.

In some embodiments, a substantially curved edge connects the top face and the body portion. In some embodiments, a substantially curved edge connects the base and the body portion.

The aerosol-generating device may comprise a user interface and/or an indicator arranged in the front face of the housing. Alternatively, or additionally, the aerosol-generating device may comprise a charging port provided in an aperture arranged in the first or second side portion.

The aerosol-generating device may comprise a slidable cover arranged at the top face of the housing and configured to cover an opening of the heating assembly in a first position and not cover the opening in a second position. The slidable cover may have a thickness of 5 mm or less.

The housing of the device may have a characteristic shape in the first plane, the characteristic shape being substantially the same along at least 50% of the extent of the housing in the first direction. In one embodiment, the characteristic shape is formed from an isosceles trapezoid having a height (h) of not more than 25 mm, the first base of the trapezoid being provided with a first convex portion extending along the entire first base, and the second base of the trapezoid being provided with a second convex portion extending along the entire second base. Preferably, each convex portion is substantially semi-circular. More preferably still, the radius (r_1) of the first convex portion is not more than 12 mm, and radius (r_2) of the second convex portion is not more than 11 mm.

In some embodiments, the heating assembly of the aerosol-generating device may comprise an induction heating unit.

In some embodiments, the heating assembly is operable in a plurality of modes.

According to a second aspect of the invention, there is provided a housing for an aerosol-generating device. The housing has a characteristic extent in a first direction of not more than 85 mm, a characteristic extent in a second direction perpendicular to the first direction of not more than 45 mm, and a characteristic extent in a third direction perpendicular to the first and second directions of not more than 23 mm. The housing further has a characteristic shape in a first plane perpendicular to the first direction, the characteristic shape being formed from an isosceles trapezoid having a height (h) of not more than 25 mm, the first base of the trapezoid being provided with a first convex portion extending along the entire first base, and the second base of the trapezoid being provided with a second convex portion extending along the entire second base.

In one embodiment, the housing has a characteristic shape in a second plane perpendicular to the second direction, the characteristic shape being substantially right trapezoid with a height of not more than 45 mm. The obtuse angle of the right trapezoid is preferably less than 95°. In some embodiments, the corners of the shape in the second plane are rounded.

In one embodiment, the housing has a characteristic shape in a third plane perpendicular to the third direction, the characteristic shape being substantially rectangular. In some embodiments, the corners of the shape in the third plane are rounded.

According to a third aspect of the present invention, there is provided an aerosol-generating system comprising an aerosol-generating device as described hereinabove in combination with an aerosol-generating article.

According to a further aspect of the present invention there is provided a kit comprising an aerosol-generating device according to any of the above aspects in combination with a removable cover for the aerosol-generating device.

BRIEF DESCRIPTION OF THE DRAWINGS

FIG. 1A is a perspective view of an aerosol-generating device comprising a housing according to the present invention.

FIGS. 1B-D are front, side and top elevations respectively of the device.

FIG. 2 is a perspective view of an aerosol-generating device according to the present invention showing a first plane.

FIG. 3 is a front elevation of an aerosol-generating device according to the present invention showing the angle of the top face of the housing.

FIG. 4 is a side elevation of an aerosol-generating device according to the present invention showing a third plane.

FIG. 5 is a top elevation of an aerosol-generating device according to the present invention showing a second plane.

FIG. 6A is a front elevation of an aerosol-generating device according to the present invention showing a sectional plane A-A.

FIG. 6B is the outer surface of the sectional shape in the plane A-A.

FIGS. 6C and 6D show how the shape can be characterised.

FIG. 7A is a top elevation of an aerosol-generating device according to the present invention showing a sectional plane B-B.

FIG. 7B is the outer surface of the sectional shape in the plane B-B.

FIG. 8A is a side elevation of an aerosol-generating device according to the present invention showing a sectional plane C-C.

FIG. 8B is the outer surface of the sectional shape in the plane C-C.

FIG. 8C shows how the shape can be characterised.

FIG. 9A is a front elevation of a heating assembly arranged in the aerosol-generating device of the present invention.

FIG. 9B is a sectional view of the heating assembly.

FIG. 10A is a schematic cross-section of an aerosol-generating article for use with the aerosol-generating device of the present invention.

FIG. 10B is a perspective view of the aerosol-generating article.

FIG. 11 is a perspective view of a removable cover to be used in combination with an aerosol-generating device according to an example.

DETAILED DESCRIPTION

As used herein, “the” may be used to mean “the” or “the or each” as appropriate. In particular, features described in relation to “the at least one heating unit” may be applicable to the first, second or further heating units where present. Further, features described in respect of a “first” or “second” integers may be equally applicable integers. For example, features described in respect of a “first” or “second” heating unit may be equally applicable to the other heating units in

different embodiments. Similarly, features described in respect of a “first” or “second” mode of operation may be equally applicable to other configured modes of operation.

In general, reference to a “first” heating unit in the heating assembly does not indicate that the heating assembly contains more than one heating unit, unless otherwise specified; rather, the heating assembly comprising a “first” heating unit must simply comprise at least one heating unit. Accordingly, a heating assembly containing only one heating unit 10 expressly falls within the definition of a heating assembly comprising a “first” heating unit.

Similarly, reference to a “first” and “second” heating unit in the heating assembly does not necessarily indicate that the heating assembly contains two heating units only; further heating units may be present. Rather, in this example, the heating assembly must simply comprise at least a first and a second heating unit.

As used herein, the term “aerosol-generating material” includes materials that provide volatilised components upon heating, typically in the form of an aerosol. Aerosol-generating material includes any tobacco-containing material and may, for example, include one or more of tobacco, tobacco derivatives, expanded tobacco, reconstituted tobacco or tobacco substitutes. Aerosol-generating material also may include other, non-tobacco, products, which, depending on the product, may or may not contain nicotine. Aerosol-generating material may for example be in the form of a solid, a liquid, a gel, a wax or the like. Aerosol-generating material may for example also be a combination or a blend of materials. Aerosol-generating material may also be known as “smokable material”. In a preferred embodiment, the aerosol-generating material is a non-liquid aerosol-generating material. In a particularly preferred embodiment, the non-liquid aerosol-generating material comprises tobacco.

Apparatus is known that heats aerosol-generating material to volatilise at least one component of the aerosol-generating material, typically to form an aerosol which can be inhaled, without burning or combusting the aerosol-generating material. Such apparatus is sometimes described as an “aerosol-generating device”, an “aerosol provision device”, a “heat-not-burn device”, a “tobacco heating product”, a “tobacco heating product device”, a “tobacco heating device” or similar. In a preferred embodiment of the present invention, the aerosol-generating device of the present invention is a tobacco heating product. The non-liquid aerosol-generating material for use with a tobacco heating product comprises tobacco.

Similarly, there are also so-called e-cigarette devices, which are typically aerosol-generating devices which vapourise an aerosol-generating material in the form of a liquid, which may or may not contain nicotine. The aerosol-generating material may be in the form of or be provided as part of a rod, cartridge or cassette or the like which can be inserted into the apparatus. A heater for heating and volatilising the aerosol-generating material may be provided as a “permanent” part of the apparatus.

An aerosol-generating device of the present invention can receive an article comprising aerosol-generating material for heating, also referred to as a “smoking article”. An “article”, “aerosol-generating article” or “smoking article” in this context is a component that includes or contains in use the aerosol-generating material, which is heated to volatilise the aerosol-generating material, and optionally other components in use. A user may insert the article into the aerosol-generating device before it is heated to produce an aerosol, which the user subsequently inhales. The article may be, for

example, of a predetermined or specific size that is configured to be placed within a heating chamber of the device which is sized to receive the article.

The aerosol-generating device of the present invention comprises a heating assembly. The heating assembly comprises at least one heating unit arranged to heat, but not burn, the aerosol-generating material in use.

A heating unit typically refers to a component which is arranged to receive electrical energy from an electrical energy source, and to supply thermal energy to an aerosol-generating material. A heating unit comprises a heating element. A heating element is typically a material which is arranged to supply heat to an aerosol-generating material in use. The heating unit comprising the heating element may comprise any other component required, such as a component for transducing the electrical energy received by the heating unit. In other examples, the heating element itself may be configured to transduce electrical energy to thermal energy.

The heating unit may comprise a coil. In some examples, the coil is configured to, in use, cause heating of at least one electrically-conductive heating element, so that heat energy is conductible from the at least one electrically-conductive heating element to aerosol generating material to thereby cause heating of the aerosol generating material.

In some examples, the coil is configured to generate, in use, a varying magnetic field for penetrating at least one heating element, to thereby cause induction heating and/or magnetic hysteresis heating of the at least one heating element. In such an arrangement, the or each heating element may be termed a "susceptor". A coil that is configured to generate, in use, a varying magnetic field for penetrating at least one electrically-conductive heating element, to thereby cause induction heating of the at least one electrically-conductive heating element, may be termed an "induction coil" or "inductor coil".

The device may include the heating element(s), for example electrically-conductive heating element(s), and the heating element(s) may be suitably located or locatable relative to the coil to enable such heating of the heating element(s). The heating element(s) may be in a fixed position relative to the coil. Alternatively, the at least one heating element, for example at least one electrically-conductive heating element, may be included in an article for insertion into a heating zone of the device, wherein the article also comprises the aerosol generating material and is removable from the heating zone after use. Alternatively, both the device and such an article may comprise at least one respective heating element, for example at least one electrically-conductive heating element, and the coil may be to cause heating of the heating element(s) of each of the device and the article when the article is in the heating zone.

In some examples, the coil is helical. In some examples, the coil encircles at least a part of a heating zone of the device that is configured to receive aerosol generating material. In some examples, the coil is a helical coil that encircles at least a part of the heating zone.

In some examples, the device comprises an electrically-conductive heating element that at least partially surrounds the heating zone, and the coil is a helical coil that encircles at least a part of the electrically-conductive heating element. In some examples, the electrically-conductive heating element is tubular. In some examples, the coil is an inductor coil.

In some examples, the heating unit is an induction heating unit. In some examples, the heating unit is a resistive heating unit. A resistive heating unit may consist of a resistive

heating element. That is, it may be unnecessary for a resistive heating unit to include a separate component for transducing the electrical energy received by the heating unit, because a resistive heating element itself transduces electrical energy to thermal energy.

The heating assembly may also comprise a controller for controlling each heating unit present in the heating assembly. The controller may be a PCB. The controller is configured to control the power supplied to each heating unit, and 10 controls the "programmed heating profile" of each heating unit present in the heating assembly. For example, the controller may be programmed to control the current supplied to a plurality of inductors to control the resulting 15 temperature profiles of the corresponding induction heating elements. As between the temperature profile of heating elements and aerosol-generating material described above, the programmed heating profile of a heating element may not exactly correspond to the observed temperature profile of a heating element, for the same reasons given above.

20 The heating assembly may be operable in at least a first mode and a second mode. The heating assembly may be operable in a maximum of two modes, or may be operable in more than two modes, such as three modes, four modes, or five modes.

25 The device of the present disclosure may be configured to operate in this manner by a controller of the heating assembly being programmed to operate the device in the plurality of modes. Accordingly, references herein to the configuration of the device of the present invention or components 30 thereof may refer to the controller of the heating assembly being programmed to operate the device as disclosed herein.

35 Each mode may be associated with a predetermined heating profile for each heating unit in the heating assembly, such as a programmed heating profile. For example, the heating assembly may be arranged such that the controller receives a signal identifying a selected mode of operation, and instructs the or each heating element present in the heating assembly to operate according to a predetermined heating profile. The controller selects which predetermined 40 heating profile to instruct the or each heating unit based on the signal received.

45 One or more of the programmed heating profiles may be programmed by a user. Alternatively, or additionally, one or more of the programmed heating profiles may be programmed by the manufacturer. In these examples, the one or more programmed heating profiles may be fixed such that an end-user cannot alter the one or more programmed heating profiles.

50 "Session of use" as used herein refers to a single period of use of the aerosol-generating device by a user. The session of use begins at the point at which power is first supplied to at least one heating unit present in the heating assembly. The device will be ready for use after a period of time has elapsed from the start of the session of use. The session of use ends 55 at the point at which no power is supplied to any of the heating elements in the aerosol-generating device. The end of the session of use may coincide with the point at which the smoking article is depleted (the point at which the total particulate matter yield (mg) in each puff would be deemed unacceptable low by a user). The session will have a duration of a plurality of puffs. Said session may have a duration less than 7 minutes, or 6 minutes, or 5 minutes, or 4 minutes and 30 seconds, or 4 minutes, or 3 minutes and 30 seconds. In some embodiments, the session of use may have 60 a duration of from 2 to 5 minutes, or from 3 to 4.5 minutes, or 3.5 to 4.5 minutes, or suitably 4 minutes. A session may be initiated by the user actuating a button or switch on the

device, causing at least one heating element to begin rising in temperature. A session may end at after a predetermined duration, such as a programmed duration in a controller. A session is also considered to end if a user deactivates the device, such as before the programmed end of the session of use (deactivation of the device will terminate power being supplied to any of the heating elements in the aerosol-generating device).

“Operating temperature” as used herein in relation to a heating element or a heating unit refers to any heating element temperature at which the element can heat an aerosol-generating material to produce sufficient aerosol for a satisfactory puff without burning the aerosol-generating material. The maximum operating temperature of a heating element is the highest temperature reached by the element during a session of use. The lowest operating temperature of the heating element refers to the lowest heating element temperature at which sufficient aerosol can be generated from the aerosol-generating material by the heating element for a satisfactory puff. Where there is a plurality of heating elements present in the aerosol-generating device, each heating element has an associated maximum operating temperature. The maximum operating temperature of each heating element may be the same, or it may differ for each heating element.

In some embodiments, each mode of operation of the heating assembly may be associated with a predetermined duration for a session of use (i.e. a predetermined duration for a session of use), or a predetermined maximum operating temperature. In some embodiments, the session of use duration associated with at least one mode differs from the session of use duration(s) associated with other modes. In some embodiments, each mode may be associated with different predetermined durations of session of use. In particular, the first mode may be associated with a first session of use duration, and the second mode may be associated with a second session of use duration. The first session of use duration may differ from the second session of use duration. Preferably, the first session of use duration is longer than the second session of use duration. In some examples, the first and/or second session of use may have a duration of at least 2 minutes, 2 minutes 30 seconds, 3 minutes, 3 minutes 30 seconds, 4 minutes, 4 minutes 30 seconds, 5 minutes, 5 minutes 30 seconds, or 6 minutes. In some examples, the first and/or second session of use may have a duration of less than 7 minutes, 6 minutes, 5 minutes 30 seconds, 5 minutes, 4 minutes 30 seconds, or 4 minutes. Preferably, the first session of use has a duration of from 3 minutes to 5 minutes, more preferably from 3 minutes 30 seconds to 4 minutes 30 seconds. Preferably, the second session of use has a duration of from 2 minutes to 4 minutes, more preferably from 2 minutes 30 seconds to 3 minutes 30 seconds.

Each mode may be associated with a maximum temperature to which the or each heating unit in the heating assembly rises in use. In some embodiments, the heating assembly is configured such that the first heating unit reaches a first-mode maximum operating temperature in the first mode, and a second-mode maximum operating temperature in the second mode. The maximum operating temperature of the first heating unit in the first mode (herein referred to as the “first-mode maximum operating temperature” of the first heating unit) may differ from the maximum operating temperature of the first heating unit in the second mode (herein referred to as the “second-mode maximum operating temperature” of the first heating unit). In some examples, the first mode maximum operating temperature is

higher than the second-mode maximum operating temperature; in other examples, the first-mode maximum operating temperature is lower than the second-mode maximum operating temperature. Preferably, the second-mode maximum operating temperature of the first heating unit is higher than the first-mode maximum operating temperature of the first heating unit.

The device of the present invention comprises a housing. The housing is generally the aspect of the device which a user interacts with most. It is therefore important to provide a housing with a pleasing visual appearance as well as an ergonomically comfortable shape. Surprisingly, it has been found that relatively minor variations in physical parameters of an aerosol-generating device housing can provide large differences in the extent that the device is ergonomic, and the degree of user satisfaction. In some embodiments, at least a portion of the housing may be provided with a coating. In a particular embodiment, a portion of the housing comprises a soft-touch coating.

20 The configuration of the housing and (optionally) the coating may reduce the surface temperature reached by the device during operation compared with another device. In some embodiments, during a session of use, the surface of the device reaches a temperature of less than 55° C., preferably 50° C., more preferably 48° C., most preferably 45° C.

25 According to one aspect of the present invention there is provided a kit comprising an aerosol-generating device for generating aerosol from an aerosol-generating material, in combination with a removable cover for the aerosol-generating device. The removable cover may also be referred to as a “sleeve”. The aerosol-generating device may be any suitable aerosol-generating device, such as an aerosol-generating device as described herein. In some examples according to this aspect, the housing of the aerosol-generating device has a soft-touch coating; in other examples, the housing of the aerosol-generating device does not have a soft-touch coating.

30 The removable cover has an inner surface which is configured such that, when the cover is provided on the aerosol-generating device, the inner surface contacts at least a portion of the housing of the aerosol-generating device. In examples, the inner surface defines a volume within which the aerosol-generating device may be arranged in use.

35 The removable cover typically has an opening through which the aerosol-generating device can be supplied to the volume or removed from the volume; the removable cover can be applied to/removed from the device by sliding the removable cover relative to the device. In examples, the removable cover is open at two ends (typically opposite ends), and the removable cover defines a lumen (the volume) which extends along an axis between the open ends.

40 The removable cover has an outer surface which is configured such that, when the cover is provided on the aerosol-generating device, a user can touch the outer surface of the removable cover when interacting with the aerosol-generating device. In examples, the removable cover forms a barrier between at least a portion of the housing of the aerosol-generating device and a user. The present inventors have identified that, when the removable cover is arranged around the aerosol-generating device during operation of the device, the outer surface of the removable cover typically has a surface temperature which is lower than the surface temperature of the housing.

45 The removable cover may comprise any suitable material. In examples, substantially all of the removable cover is formed of the same material. In examples, the removable

cover comprises a thermal insulator. In examples the removable cover is fibrous, e.g. comprises textile fibres. In examples the removable cover is an elastomer, e.g. the removable cover comprises and/or consists of silicone. An elastomeric removable cover is easily removed from around an aerosol-generating device when desired, and retains the aerosol-generating device within the cover well when desired.

Advantageously, the inventors have identified that providing an aerosol-generating device with a removable cover comprising a thermal insulator reduces the surface temperature experienced by a user during use of the aerosol-generating device, thereby providing an improved user experience.

Further, providing an aerosol-generating device in combination with a removable cover may provide a more desirable appearance by, for example, the removable cover having a distinctive colour or surface pattern.

The removable cover typically comprises one or more apertures through which a user can interact with the device. In examples, the removable cover comprises an aperture which corresponds to a user interface and/or indicator of the device, e.g. the removable cover is configured such that, when the device is arranged within the removable cover, the aperture is positioned around the user interface and/or indicator such that the removable cover does not cover the user interface and/or indicator of the device. The user interface typically comprises an actuator for controlling the device and/or a display. In examples, the removable cover comprises an aperture which corresponds to a socket/port for receiving a cable to charge a battery of the device, e.g. the removable cover is configured such that, when the device is arranged within the removable cover, the aperture is positioned around the socket/port such that a power cable can pass through the aperture to the socket/port.

Further aspects of the present invention will be now be described with respect to the drawings.

FIG. 1A is a perspective view of an aerosol-generating device 100 according to the present invention; FIG. 1B is a front elevation of the device 100; FIG. 1C is a side elevation of the device 100; FIG. 1D is a top elevation of the device 100.

The device 100 comprises a housing 102. The housing may comprise a base 104, a top face 106, a front face 108, a rear face 110, a first side portion 112, and a second side portion 114.

The housing extends in a first direction 120, a second direction 122, and a third direction 124. Each direction is perpendicular to the other directions; the first, second and third directions 120, 122, 124 define a three-dimensional space.

FIGS. 2A to 2C further indicate the first, second and third directions 120, 122, 124 and the extent of the housing 102. In the first direction 120 the housing 102 has a characteristic extent 130 of not more than 85 mm. Preferably, the extent 130 in the first direction 120 is more than 70 mm, more than 75 mm, or more than 80 mm. Suitably, the extent 130 in the first direction 120 is 82 mm. The characteristic extent 130 in the first direction 120 may conveniently be referred to as the height 130 of the housing 102, and refers to the greatest extent of the housing in that direction.

In the second direction 122 the housing 102 has a characteristic extent 132 of not more than 45 mm. Preferably, the extent 132 in the second direction 122 is more than 30 mm, 35 mm, or 40 mm. Suitably, the extent 132 in the second direction 122 is 43 mm. The characteristic extent 132 in the second direction 122 may conveniently be referred to as the

width 132 of the housing 102, and refers to the greatest extent of the housing 102 in the second direction 122.

In the third direction 124 the housing 102 has a characteristic extent 134 of not more than 23 mm. Preferably, the extent 134 in the third direction 124 is more than 10 mm, 15 mm, or 20 mm. Suitably, the extent 134 in the third direction 124 is 21 mm.

It has been found by the inventors that a housing 102 having the parameters set out above is surprisingly suitable for being held in a user's hand. These dimensions present an ergonomic device which may be more satisfying to a user during a session of use.

Inside the housing 102 there is disposed a heating assembly (not shown) for receiving aerosol-generating material, preferably in the form of an aerosol-generating article. The heating assembly is configured to heat aerosol-generating material received in the heating assembly. For example, the heating assembly may define a chamber in which the aerosol-generating article can be received, and comprise one or more heating units arranged around the chamber for externally heating the aerosol-generating article. In another embodiment, the heating assembly may comprise a heating unit configured to be inserted into an aerosol-generating article received in the heating assembly, such that in use the heating unit internally heats the aerosol-generating article, i.e. heats the aerosol-generating material from inside the aerosol-generating article. The heating assembly defines an aperture 140 through which an aerosol-generating article may be inserted to the heating assembly. The aperture 140 is preferably arranged in the top surface 106 of the housing 102.

The device optionally includes a slidable cover 142 arranged in a portion of the housing 102. In the device shown in FIGS. 1A to 1D, the slidable cover 142 is arranged on the top face 106. The slidable cover 142 is arranged such that a user can position the slidable cover 142 in at least a first position and a second position. The slidable cover 142 is configured such that, in the first position, the slidable cover covers the aperture 140, thereby prohibiting undesired material from entering the heating assembly. The slidable cover 142 is also configured such that, in a second position, the slidable cover 142 does not cover the aperture 140, allowing for the insertion of an aerosol-generating article.

The device also comprises a user interface 144 for a user to activate the device 100, the user interface being arranged in a portion of the housing. Optionally, the user interface 144 may also be configured such that a user may select a desired mode of operation of the device 100 by interacting with the user interface 144 in a predetermined manner.

The device further comprises an indicator 146 for indicating the operation of the device 100 to a user. For example, the indicator 146 may be configured to indicate that the device 100 is turned on, and/or that a heating session is in progress. Further, in embodiments wherein the device 100 is operable in a plurality of modes, the indicator 146 may indicate the selected mode of operation to the user.

Preferably, the user interface 144 and indicator 146 are arranged together in a surface of the housing 102. In a particularly preferred embodiment as shown in FIG. 1, the indicator 146 is arranged to surround the user interface 144.

The housing may include an aperture 148 for receiving an electrical connector/component of the device, such as a socket/port, which can receive a cable to charge a battery of the device 100. For example, the socket may be a charging port, such as a USB charging port. In some examples the socket may be used additionally or alternatively to transfer data between the device 100 and another device, such as a

11

computing device. Preferably, the aperture 148 is provided in the first side portion 112 or the second side portion 114. This configuration may allow for the device 100 to receive electrical charge which resting on the base 104 on a flat surface. In a particularly preferred embodiment, a battery is arranged within the housing closer to the first side portion 112 than the second side portion, the aperture 148 is provided in the first side portion 112, and a charging port is arranged in the aperture 148.

The housing 102 may also be provided with a contrast feature 150. The contrast feature 150 may be provided with a different colour, and may advantageously be used to indicate the model of the device. The contrast feature 150 may be formed of a pigment layer (i.e. provided by painting) and substantially flush with the surface of the housing 102. Alternatively, the contrast feature 150 may be machined. For example, the contrast feature 150 may form an indentation across the surface of the housing. Optionally, the contrast feature 150 may be provided with a different finish.

The housing may be formed of any suitable material. In a preferred embodiment, at least a portion of the housing comprises aluminium. For example, at least 50%, 60%, 70%, or 80% by weight of the housing 102 may be formed of aluminium. In a particularly preferred embodiment, at least a portion of the housing 102 comprises anodized aluminium. For example, the housing 102 have an aluminium metal base covered with an anodized aluminium layer.

FIG. 2 shows device 100. The housing 102 comprises a base 104. The base is arranged in a first plane 160 which is normal to the first direction 120. The first plane 160 extends along the second direction 122 and the third direction 124. Such an arrangement may provide an aerosol-generating device 100 which may conveniently be rested on a flat surface in between use. Moreover, when the base 104 is substantially planar as shown in the present figures, the device 100 may be displayed in a stationary manner on a flat surface.

Features of the device may alternatively be arranged in a second plane 162 normal to the second direction 122 and extending in the first and third directions 120, 124, or in a third plane 164 normal to the third direction 124 and extending in the first and second directions 120, 122. Further reference will be made to the second and third planes 162, 164, hereinbelow.

The housing 102 also comprises a top face 106. The top face is arranged to be opposed from the base 104 across the plane 160. The top face may be substantially coplanar with the base 104 and lie in the first plane 160. Preferably, though, the top face is not coplanar with the base 104. Rather, as shown in FIG. 3, the top face preferably extends in a fourth plane 166. The fourth plane 166 extends in the third direction 124, and forms a dihedral angle $\theta_{160-166}$ with the first plane 160. The dihedral angle $\theta_{160-166}$ thus corresponds to the angle between the base 104 and the top face 106. The dihedral angle $\theta_{160-166}$ is greater than 0°. The dihedral angle $\theta_{160-166}$ is preferably less than 5°, more preferably less than 4°, still more preferably less than 3°. The dihedral angle is preferably greater than 0.5°, 1°, 1.5°, or 2°. In a preferred embodiment, the dihedral angle is approximately 2.5°. The inventors have found that a top face which is arranged with a slope as defined herein may feel more comfortable to a user when the device is held in the hand.

The fourth plane 166 may also be defined as extending in the third direction 124 and a fourth direction 126. The fourth direction is perpendicular to the third direction 124 and $-\theta_{160-166}$ from the second direction 122.

12

In a particularly preferred embodiment, the dihedral angle $\theta_{160-166}$ is less than 5° C., and the sliding cover 142 is configured to be slidable along an axis in the fourth direction 126. The inventors have found that this configuration is more comfortable for a user when moving the sliding cover 142 to reveal or cover the aperture 140. The sliding cover 142 may be arranged to be substantial parallel with the top face 106. In one embodiment, the sliding door has a thickness of less than 10 mm, or 9 mm, or 8 mm, or 7 mm, or 6 mm, or 5 mm, or 4 mm, or 3 mm, or 2 mm. The thickness of the sliding cover 142 is defined as the extent of the sliding door in a direction perpendicular to the fourth plane 166. The sliding cover may be provided with a grooved texture on the top surface of the sliding cover. Advantageously, this grooved texture may mean that the sliding door may be moved by a user more easily because it provides a greater grip.

The base 104 and top face 106 are connected by a body portion. The body portion comprises the front face 108, the rear face 110, the first side portion 112, and the second side portion 114.

As shown in FIG. 4, the front face 108 and the rear face 110 extend from the base 104 to the top face 106. The front face 108 is arranged opposite to the rear face 110; preferably the front face 108 is arranged opposed to the rear face 110 across the third plane 164. The front face 108 is connected to the base 104 by a curved edge. The front face 108 is connected to the top face 106 by a curved edge. Similarly, the rear face 110 is connected to the base 104 by a curved edge. The rear face 110 is connected to the top face 106 by a curved edge. Front face 108 and rear face 110 both extend in the first direction. However, the front face 108 and rear face 110 are preferably not parallel. Preferably, neither the front face 108 nor the rear face 110 are curved; preferably the front face 108 and/or the rear face 110 is planar.

Referring back to FIG. 3, the first side portion 112 and the second side portion 114 extend from the base 104 to the top face 106. The first side portion 112 is connected to the base 104 by a curved edge. The first side portion 112 is connected to the top face 106 by a curved edge. Similarly, the second side portion 114 is connected to the base 104 by a curved edge. The second side portion 114 is connected to the top face 106 by a curved edge.

As shown in FIG. 5, the first side portion 112 connects the front face 108 and rear face 110 at a first edge of the faces 108, 110, and the second side portion 114 connects the front face 108 and rear face 110 at a second edge of the faces 108, 110. The first side portion 112 is arranged opposite to the second side portion 114. Preferably, the first side portion 112 is arranged opposed to the second side portion 114 across the second plane 162.

The first side portion 112 and second side portion 114 both extend in the first direction. Preferably, each side portion is curved in the first plane 160.

Preferably each edge connecting the body portion and the top face 106 is curved. Similarly, it is preferred that each edge connecting the body portion and the base 104 is curved.

In a preferred embodiment, the shape of the housing 102 is substantially symmetrical across the third plane 164 (that is, the portion on the left of the plane 164 in FIG. 4 is symmetrical to the portion on the right of the plane 164 in FIG. 4). The inventors have found that users may find a device 100 which is configured to be symmetrical in this manner may be held more comfortably in the hand. In a further embodiment, the shape of the housing 102 is preferably asymmetrical across the second plane 162 and the first plane 160. In particular, it is preferable that the extent

13

of the device in the third direction 124 is not constant along the second direction 122 of the housing 102. Again, the inventors have found that users may find a device 100 which is configured to be symmetrical in this manner may be held more comfortably in the hand.

The housing 102 may have an outer cross-sectional characteristic shape in the first plane 160, second plane 162 and/or third plane 164. As used herein, "cross-sectional characteristic shape" refers only to the external shape of the housing, i.e. the perimeter shape of the cross-section. The internal shape of the housing 102 is not taken into account.

Preferably, the housing 102 has substantially the same cross-sectional characteristic shape in the first plane 160 along at least 50% of the extent of the housing in the first direction 120, or 60%, 70%, 80%, 90%, or more than 90%. In a preferred embodiment, the housing 102 has substantially the same cross-sectional characteristic shape in the first plane 160 along more than 90% of the extent of the housing 102 in the first direction 120. In this context, two shapes are considered to be the same if they are "similar" in the mathematical sense: the angles between the sides of the shape are the same, and the ratios between the corresponding sides are the same. Put another way, the internal proportions of the shapes must be the same, but not necessarily the absolute size. Thus, a housing having a first cross-sectional shape at a first point along the first direction and a second cross-sectional shape at a second point along the first direction, wherein the second shape is an enlargement of the first shape, is considered to have the same cross-sectional characteristic shape at both points.

Preferably, the housing 102 has substantially the same cross-sectional characteristic shape and size in the first plane 160 along at least 50% of the extent of the housing in the first direction 120, or 60%, 70%, 80%, 90%, or more than 90%. In a preferred embodiment, the housing 102 has substantially the same cross-sectional characteristic shape and size in the first plane 160 along more than 90% of the extent of the housing 102 in the first direction 120. In this context, two shapes are considered to have the same shape and size if they are "congruent" in the mathematical sense: the angles between the sides of the shape are the same, and the absolute size of the sides is the same.

In examples, the housing 102 has a thickness (e.g. the shortest distance between a point on the outer surface of the housing 102 and the inner surface of the housing 102). The housing 102 typically has an average thickness (e.g. the mean of shortest distances taken between a plurality of points on the outer surface and corresponding points on the inner surface) of from about 0.8 to about 1.6 mm. In one example, the average thickness is approximately 0.975 mm. In another example, the average thickness is approximately 1.5 mm. Advantageously, this example with the greater thickness may have a lower outer surface temperature during operation.

FIG. 6A shows the device 100 with the first plane 160 marked. The first plane 160 is coplanar with the base 104. Section A-A is taken along the first plane 160. FIG. 6B shows a cross-sectional characteristic shape 170 of the housing 102 in the first plane 160, the section being taken through the plane A-A.

The cross-sectional characteristic shape 170 may be characterized as a combination of regular two-dimensional shapes. For example, the characteristic shape 170 may be formed from an isosceles trapezoid 172 in combination with a first convex portion 174 and second convex portion 176, as shown in FIGS. 6C and 6D.

14

Isosceles trapezoid 172 forms the center portion of the shape, and contains the internal angles α and β : $\alpha=\alpha$, $\beta=\beta$, and $\alpha \neq \beta$. The height h of the isosceles trapezoid 172 is preferably not more than 25 mm. The height h may be more than 10 mm, 15 mm, or 20 mm. Suitably, the height h of the trapezoid 172 is approximately 24 mm.

A trapezoid has a pair of parallel sides (the "bases") and a pair of non-parallel sides (the "legs"). The legs of trapezoid 172 are equal in length; base a is longer than base b .

The first convex portion 174 is arranged across the entirety of base a . That is, the base of the first convex portion 174 has the same length as base a . Preferably, as shown in FIGS. 6C and 6D, the first convex portion 174 is substantially semi-circular. In this embodiment, the first convex portion 174 has a radius r_1 , and $a=2r_1$.

The radius r_1 of the semi-circular first convex portion 174 is not more than 12 mm. The radius r_1 may be more than 5 mm, 8 mm or 10 mm. Suitably, the radius r_1 is between 10 mm and 11 mm. Hence, base a is not more than 24 mm, and is suitably approximately 23 mm.

The second convex portion 176 is arranged across the entirety of base b . That is, the base of the second convex portion 176 has the same length as base b . Thus, $b=2r_2$. Preferably, as shown in FIGS. 6C and 6D, the second convex portion 176 is substantially semi-circular. In this embodiment, the second convex portion 176 has a radius r_2 , and $b=2r_2$.

The radius r_2 of the semi-circular second convex portion 176 is not more than 11 mm. The radius r_2 may be more than 5 mm, 7 mm or 9 mm. Suitably, the radius r_2 is approximately 9 mm. Hence, base b is not more than 22 mm, and is suitably approximately 18 mm.

Preferably, the housing 102 has substantially the same cross-sectional characteristic shape in the second plane 162 along not more the 20% of the extent of the housing in the second direction 122, or 10%, 5%, 4%, 3%, 2%, or 1%. In a preferred embodiment, the housing 102 has substantially the same cross-sectional characteristic shape along no more than 1% of the extent of the housing 102 in the second direction 122. In this context, two shapes are considered to be the same if they are "similar" in the mathematical sense: the angles between the sides of the shape are the same, and the ratios between the corresponding sides are the same. Put another way, the internal proportions of the shapes must be the same, but not necessarily the absolute size. Thus, a housing having a first cross-sectional shape at a first point along the second direction and a second cross-sectional shape at a second point along the second direction, wherein the second shape is an enlargement of the first shape, is considered to have the same cross-sectional characteristic shape at both points.

Preferably, the housing 102 has substantially the same cross-sectional characteristic shape and size in the first plane 160 along not more the 20% of the extent of the housing in the second direction 122, or 10%, 5%, 4%, 3%, 2%, or 1%. In a preferred embodiment, the housing 102 has substantially the same cross-sectional characteristic shape and size along no more than 1% of the extent of the housing 102 in the first direction. In this context, two shapes are considered to have the same shape and size if they are "congruent" in the mathematical sense: the angles between the sides of the shape are the same, and the absolute size of the sides is the same.

FIG. 7A shows the device 100 with the second plane 162 marked. Section B-B is taken along the second plane 162.

15

FIG. 7B shows a cross-sectional characteristic shape **180** of the housing **102** in the second plane **162**, the section being taken through the plane B-B.

The cross-sectional characteristic shape **180** shown in FIG. 7B may be characterized as substantially rectangular. The characteristic shape **180** preferably has rounded corners, as shown in FIG. 7B.

Preferably, the housing **102** has substantially the same cross-sectional characteristic shape in the third plane **164** along at least 50% of the extent of the housing in the third direction **124**, or 60%, 70%, 80%, 90%, or more than 90%. In a preferred embodiment, the housing **102** has substantially the same cross-sectional characteristic shape in the third plane **164** along more than 90% of the extent of the housing **102** in the third direction **124**. In this context, two shapes are considered to be the same if they are "similar" in the mathematical sense: the angles between the sides of the shape are the same, and the ratios between the corresponding sides are the same. Put another way, the internal proportions of the shapes must be the same, but not necessarily the absolute size. Thus, a housing having a first cross-sectional shape at a first point along the third direction and a second cross-sectional shape at a second point along the third direction, wherein the second shape is an enlargement of the first shape, is considered to have the same cross-sectional characteristic shape at both points.

Preferably, the housing **102** has substantially the same cross-sectional characteristic shape and size in the third plane **164** along at least 50% of the extent of the housing in the third direction **124**, or more than 60%. In a preferred embodiment, the housing **102** has substantially the same cross-sectional characteristic shape and size in the third plane **164** along more than 60% of the extent of the housing **102** in the third direction **124**. In this context, two shapes are considered to have the same shape and size if they are "congruent" in the mathematical sense: the angles between the sides of the shape are the same, and the absolute size of the sides is the same.

FIG. 8A shows the device **100** with the third plane **164** marked. Section C-C is taken along the first plane **160**. FIG. 8B shows a cross-sectional characteristic shape **190** of the housing **102** in the third plane **164**, the section being taken through the plane C-C.

The cross-sectional characteristic shape **190** shown in FIG. 8B may be characterized as substantially right trapezoid, as shown in FIG. 8C. A right trapezoid contains two right angles.

The longer base *a* has a length of not more than 85 mm. Preferably, the base *a* has a length of more than 70 mm, or more than 75 mm, or more than 80 mm. The trapezoid **190** may have a height *h* of not more than 45 mm. Preferably, height *h* is more than 30 mm, 35 mm, or 40 mm. Suitably, the height *h* is 43 mm.

Aside from the two right angles, the internal angles of the trapezoid **190** are θ_1 , the acute angle, and θ_2 , the obtuse angle. Preferably, the obtuse angle θ_2 is not more than 95°, or 94° or 93°. Suitably the obtuse angle θ_2 is approximately 92°.

Preferably, as shown in FIG. 8B, the square trapezoid shape **190** has rounded corners.

FIG. 9A shows an induction heating assembly **200** of an aerosol-generating device according to the present invention; FIG. 1B shows a cross section of the induction heating assembly **200** of the device.

The heating assembly **200** has a first or proximal or mouth end **202**, and a second or distal end **204**. In use, the user will

16

inhale the formed aerosol from the mouth end of the aerosol-generating device. The mouth end may be an open end.

The heating assembly **200** comprises a first induction heating unit **210** and a second induction heating unit **220**. The first induction heating unit **210** comprises a first inductor coil **212** and a first heating element **214**. The second induction heating unit **220** comprises a second inductor coil **222** and a second heating element **224**.

FIGS. 9A and 9B show a smoking article **230** received within a susceptor **240**. The susceptor **240** forms the first induction heating element **214** and the second induction heating element **224**. The susceptor **240** may be formed from any material suitable for heating by induction. For example, the susceptor **240** may comprise metal. In some embodiments, the susceptor **240** may comprise non-ferrous metal such as copper, nickel, titanium, aluminium, tin, or zinc, and/or ferrous material such as iron, nickel or cobalt. Additionally, or alternatively the susceptor **240** may comprise a semiconductor such as silicon carbide, carbon or graphite.

Each induction heating element present in the aerosol-generating device may have any suitable shape. In the embodiment shown in FIG. 9B, the induction heating elements **214**, **224** define a receptacle to surround an aerosol-generating article and heat the aerosol-generating article externally. In other embodiments (not shown), one or more induction heating elements may be substantially elongate, arranged to penetrate an aerosol-generating article and heat the aerosol-generating article internally.

As shown in FIG. 9B, the first induction heating element **214** and second induction heating element **224** may be provided together as a monolithic element **240**. That is, in some embodiments, there is no physical distinction between the first **214** and second **224** heating elements. Rather, the differing characteristics between the first and second heating units **210**, **220** are defined by separate inductor coils **212**, **222** surrounding each induction heating element **214**, **224**, so that they may be controlled independently from each other. In other embodiments (not depicted), physically distinct inductive heating elements may be employed.

The first and second inductor coils **212**, **222** are made from an electrically conducting material. In this example, the first and second inductor coils **212**, **222** are made from Litz wire/cable which is wound in a helical fashion to provide helical inductor coils **212**, **222**. Litz wire comprises a plurality of individual wires which are individually insulated and are twisted together to form a single wire. Litz wires are designed to reduce the skin effect losses in a conductor. In the example induction heating assembly **200**, the first and second inductor coils **224**, **226** are made from copper Litz wire which has a circular cross section. In other examples the Litz wire can have other shape cross sections, such as rectangular.

The first inductor coil **212** is configured to generate a first varying magnetic field for heating the first induction heating element **214**, and the second inductor coil **222** is configured to generate a second varying magnetic field for heating a second section of the susceptor **224**. The first inductor coil **212** and the first induction heating element **214** taken together form a first induction heating unit **210**. Similarly, the second inductor coil **222** and the second induction heating element **224** taken together form a second induction heating unit **220**.

In this example, the first inductor coil **212** is adjacent to the second inductor coil **222** in a direction along the longitudinal axis of the device heating assembly **200** (that is, the first and second inductor coils **212**, **222** do not overlap). The

susceptor arrangement 240 may comprise a single susceptor. Ends 250 of the first and second inductor coils 212, 222 can be connected to a controller such as a PCB (not shown). The PCB is preferably arranged to extend along the first plane. That is, the smallest extent of the PCB is in the first direction. This arrangement may allow for a device with a smaller extent in the first direction than a comparable device comprising a PCB arranged to have its greatest extent in the first direction. A smaller extent in the first direction may allow a user to more easily interact with the sliding door arranged on the top of the device while holding the device in one hand. In preferred embodiments, the controller comprises a PID controller (proportional integral derivative controller).

The varying magnetic field generates eddy currents within the first inductive heating element 214, thereby rapidly heating the first induction heating element 214 to a maximum operating temperature within a short period of time from supplying the alternative current to the coil 212, for example within 20, 15, 12, 10, 5, or 2 seconds. Arranging the first induction heating unit 210 which is configured to rapidly reach a maximum operating temperature closer to the mouth end 202 of the heating assembly 200 than the second induction heating unit 220 may mean that an acceptable aerosol is provided to a user as soon as possible after initiation of a session of use.

It will be appreciated that the first and second inductor coils 212, 222, in some examples, may have at least one characteristic different from each other. For example, the first inductor coil 212 may have at least one characteristic different from the second inductor coil 222. More specifically, in one example, the first inductor coil 212 may have a different value of inductance than the second inductor coil 222. In FIGS. 9A and 9B, the first and second inductor coils 212, 222 are of different lengths such that the first inductor coil 212 is wound over a smaller section of the susceptor 240 than the second inductor coil 222. Thus, the first inductor coil 212 may comprise a different number of turns than the second inductor coil 222 (assuming that the spacing between individual turns is substantially the same). In yet another example, the first inductor coil 212 may be made from a different material to the second inductor coil 222. In some examples, the first and second inductor coils 212, 222 may be substantially identical.

In this example, the first inductor coil 212 and the second inductor coil 222 are wound in the same direction. However, in another embodiment, the inductor coils 212, 222 may be wound in opposite directions. This can be useful when the inductor coils are active at different times. For example, initially, the first inductor coil 212 may be operating to heat the first induction heating element 214, and at a later time, the second inductor coil 222 may be operating to heat the second induction heating element 224. Winding the coils in opposite directions helps reduce the current induced in the inactive coil when used in conjunction with a particular type of control circuit. In one example, the first inductor coil 212 may be a right-hand helix and the second inductor coil 222 a left-hand helix. In another example, the first inductor coil 212 may be a left-hand helix and the second inductor coil 222 may be a right-hand helix.

The coils 212, 222 may have any suitable geometry. Without wishing to be bound by theory, configuring an induction heating element to be smaller (e.g. smaller pitch helix; fewer revolutions in the helix; shorter overall length of the helix), may increase the rate at which the induction heating element can reach a maximum operating temperature. In some embodiments, the first coil 212 may have a

length of less than approximately 20 mm, less than 18 mm, less than 16 mm, or a length of approximately 14 mm, in the longitudinal direction of the heating assembly 200. Preferably, the first coil 212 may have a length shorter than the second coil 224 in the longitudinal direction of the heating assembly 200. Such an arrangement may provide asymmetrical heating of the aerosol-generating article along the length of the aerosol-generating article.

The susceptor 240 of this example is hollow and therefore defines a receptacle within which aerosol-generating material is received. For example, the article 230 can be inserted into the susceptor 240. In this example the susceptor 240 is tubular, with a circular cross section.

The induction heating elements 214 and 224 are arranged to surround the smoking article 230 and heat the smoking article 230 externally. The aerosol-generating device is configured such that, when the smoking article 230 is received within the susceptor 240, the outer surface of the article 230 abuts the inner surface of the susceptor 240. This ensures that the heating is most efficient. The article 230 of this example comprises aerosol-generating material. The aerosol-generating material is positioned within the susceptor 240. The article 230 may also comprise other components such as a filter, wrapping materials and/or a cooling structure.

The heating assembly 200 is not limited to two heating units. In some examples, the heating assembly 200 may comprise three, four, five, six, or more than six heating units. These heating units may each be controllable independent from the other heating units present in the heating assembly 200.

Referring to FIGS. 10A and 10B, there is shown a partially cut-away section view and a perspective view of an example of an aerosol-generating article 300. The aerosol-generating article 300 shown in FIGS. 10A and 10B corresponds to the aerosol-generating article 230 shown in FIGS. 9A and 9B.

The aerosol-generating article 300 may be any shape suitable for use with an aerosol-generating device. The smoking article 300 may be in the form of or provided as part of a cartridge or cassette or rod which can be inserted into the apparatus. In the embodiment shown in FIGS. 9A and 9B, the smoking article 300 is in the form of a substantially cylindrical rod that includes a body of smokable material 302 and a filter assembly 304 in the form of a rod. The filter assembly 304 includes three segments, a cooling segment 306, a filter segment 308 and a mouth end segment 310. The article 300 has a first end 312, also known as a mouth end or a proximal end and a second end 314, also known as a distal end. The body of aerosol-generating material 302 is located towards the distal end 314 of the article 300. In one example, the cooling segment 306 is located adjacent the body of aerosol-generating material 302 between the body of aerosol-generating material 302 and the filter segment 308, such that the cooling segment 306 is in an abutting relationship with the aerosol-generating material 302 and the filter segment 308. In other examples, there may be a separation between the body of aerosol-generating material 302 and the cooling segment 306 and between the body of aerosol-generating material 302 and the filter segment 308. The filter segment 308 is located in between the cooling segment 306 and the mouth end segment 310. The mouth end segment 310 is located towards the proximal end 312 of the article 300, adjacent the filter segment 308. In one example, the filter segment 308 is in an abutting relationship with the mouth end segment 310. In one embodiment, the

total length of the filter assembly 304 is between 37 mm and 45 mm, more preferably, the total length of the filter assembly 304 is 41 mm.

In use, portions 302a and 302b of the body of aerosol-generating material 302 may correspond to the first induction heating element 214 and second induction heating element 224 of the portion 200 shown in FIG. 9B respectively.

The body of smokable material may have a plurality of portions 302a, 302b which correspond to the plurality of induction heating elements present in the aerosol-generating device. For example, the aerosol-generating article 300 may have a first portion 302a which corresponds to the first induction heating element 214 and a second portion 302b which corresponds to the second induction heating element 224. These portions 302a, 302b may exhibit temperature profiles which are different from each other during a session of use; the temperature profiles of the portions 302a, 302b may derive from the temperature profiles of the first induction heating element 214 and second induction heating element 224 respectively.

Where there is a plurality of portions 302a, 302b of a body of aerosol-generating material 302, any number of the substrate portions 302a, 302b may have substantially the same composition. In a particular example, all of the portions 302a, 302b of the substrate have substantially the same composition. In one embodiment, body of aerosol-generating material 302 is a unitary, continuous body and there is no physical separation between the first and second portions 302a, 302b, and the first and second portions have substantially the same composition.

In one embodiment, the body of aerosol-generating material 302 comprises tobacco. However, in other respective embodiments, the body of smokable material 302 may consist of tobacco, may consist substantially entirely of tobacco, may comprise tobacco and aerosol-generating material other than tobacco, may comprise aerosol-generating material other than tobacco, or may be free of tobacco. The aerosol-generating material may include an aerosol generating agent, such as glycerol.

In a particular embodiment, the aerosol-generating material may comprise one or more tobacco components, filler components, binders and aerosol generating agents.

The filler component may be any suitable inorganic filler material. Suitable inorganic filler materials include, but are not limited to: calcium carbonate (i.e. chalk), perlite, vermiculite, diatomaceous earth, colloidal silica, magnesium oxide, magnesium sulphate, magnesium carbonate, and suitable inorganic sorbents, such as molecular sieves. Calcium carbonate is particularly suitable. In some cases, the filler comprises an organic material such as wood pulp, cellulose and cellulose derivatives.

The binder may be any suitable binder. In some embodiments, the binder comprises one or more of an alginate, celluloses or modified celluloses, polysaccharides, starches or modified starches, and natural gums.

Suitable binders include, but are not limited to: alginate salts comprising any suitable cation, such as sodium alginate, calcium alginate, and potassium alginate; celluloses or modified celluloses, such as hydroxypropyl cellulose and carboxymethylcellulose; starches or modified starches; polysaccharides such as pectin salts comprising any suitable cation, such as sodium, potassium, calcium or magnesium pectate; xanthan gum, guar gum, and any other suitable natural gums.

A binder may be included in the aerosol-generating material in any suitable quantity and concentration.

The "aerosol-generating agent" is an agent that promotes the generation of an aerosol. An aerosol-generating agent may promote the generation of an aerosol by promoting an initial vaporisation and/or the condensation of a gas to an inhalable solid and/or liquid aerosol. In some embodiments, an aerosol-generating agent may improve the delivery of flavour from the smoking article.

In general, any suitable aerosol-generating agent or agents may be included in the aerosol-generating material. Suitable aerosol-generating agent include, but are not limited to: a polyol such as sorbitol, glycerol, and glycols like propylene glycol or triethylene glycol; a non-polyol such as monohydric alcohols, high boiling point hydrocarbons, acids such as lactic acid, glycerol derivatives, esters such as diacetin, triacetin, triethylene glycol diacetate, triethyl citrate or myristates including ethyl myristate and isopropyl myristate and aliphatic carboxylic acid esters such as methyl stearate, dimethyl dodecanedioate and dimethyl tetradecanedioate.

In a particular embodiment, the aerosol-generating material comprises a tobacco component in an amount of from 60 to 90% by weight of the tobacco composition, a filler component in an amount of 0 to 20% by weight of the tobacco composition, and an aerosol generating agent in an amount of from 10 to 20% by weight of the tobacco composition. The tobacco component may comprise paper reconstituted tobacco in an amount of from 70 to 100% by weight of the tobacco component.

In one example, the body of aerosol-generating material 302 is between 34 mm and 50 mm in length, more preferably, the body of aerosol-generating material 302 is between 38 mm and 46 mm in length, more preferably still, the body of aerosol-generating material 302 is 42 mm in length.

In one example, the total length of the article 300 is between 71 mm and 95 mm, more preferably, total length of the article 300 is between 79 mm and 87 mm, more preferably still, total length of the article 300 is 83 mm.

An axial end of the body of aerosol-generating material 302 is visible at the distal end 314 of the article 300. However, in other embodiments, the distal end 314 of the article 300 may comprise an end member (not shown) covering the axial end of the body of aerosol-generating material 302.

The body of aerosol-generating material 302 is joined to the filter assembly 304 by annular tipping paper (not shown), which is located substantially around the circumference of the filter assembly 304 to surround the filter assembly 304 and extends partially along the length of the body of aerosol-generating material 302. In one example, the tipping paper is made of 58GSM standard tipping base paper. In one example has a length of between 42 mm and 50 mm, and more preferably, the tipping paper has a length of 46 mm.

In one example, the cooling segment 306 is an annular tube and is located around and defines an air gap within the cooling segment. The air gap provides a chamber for heated volatilised components generated from the body of aerosol-generating material 302 to flow. The cooling segment 306 is hollow to provide a chamber for aerosol accumulation yet rigid enough to withstand axial compressive forces and bending moments that might arise during manufacture and whilst the article 300 is in use during insertion into the device 100. In one example, the thickness of the wall of the cooling segment 306 is approximately 0.29 mm.

The cooling segment 306 provides a physical displacement between the aerosol-generating material 302 and the filter segment 308. The physical displacement provided by the cooling segment 306 will provide a thermal gradient across the length of the cooling segment 306. In one

example the cooling segment 306 is configured to provide a temperature differential of at least 40° C. between a heated volatilised component entering a first end of the cooling segment 306 and a heated volatilised component exiting a second end of the cooling segment 306. In one example the cooling segment 306 is configured to provide a temperature differential of at least 60° C. between a heated volatilised component entering a first end of the cooling segment 306 and a heated volatilised component exiting a second end of the cooling segment 306. This temperature differential across the length of the cooling element 306 protects the temperature sensitive filter segment 308 from the high temperatures of the aerosol-generating material 302 when it is heated by the heating assembly 200 of the device aerosol-generating device. If the physical displacement was not provided between the filter segment 308 and the body of aerosol-generating material 302 and the heating elements 214, 224 of the heating assembly 200, then the temperature sensitive filter segment 308 may become damaged in use, so it would not perform its required functions as effectively.

In one example the length of the cooling segment 306 is at least 15 mm. In one example, the length of the cooling segment 306 is between 20 mm and 30 mm, more particularly 23 mm to 27 mm, more particularly 25 mm to 27 mm and more particularly 25 mm.

The cooling segment 306 is made of paper, which means that it is comprised of a material that does not generate compounds of concern, for example, toxic compounds when in use adjacent to the heater assembly 100 of the aerosol-generating device. In one example, the cooling segment 306 is manufactured from a spirally wound paper tube which provides a hollow internal chamber yet maintains mechanical rigidity. Spirally wound paper tubes are able to meet the tight dimensional accuracy requirements of high-speed manufacturing processes with respect to tube length, outer diameter, roundness and straightness.

In another example, the cooling segment 306 is a recess created from stiff plug wrap or tipping paper. The stiff plug wrap or tipping paper is manufactured to have a rigidity that is sufficient to withstand the axial compressive forces and bending moments that might arise during manufacture and whilst the article 300 is in use during insertion into the device 100.

For each of the examples of the cooling segment 306, the dimensional accuracy of the cooling segment is sufficient to meet the dimensional accuracy requirements of high-speed manufacturing process.

The filter segment 308 may be formed of any filter material sufficient to remove one or more volatilised compounds from heated volatilised components from the smokable material. In one example the filter segment 308 is made of a mono-acetate material, such as cellulose acetate. The filter segment 308 provides cooling and irritation-reduction from the heated volatilised components without depleting the quantity of the heated volatilised components to an unsatisfactory level for a user.

The density of the cellulose acetate tow material of the filter segment 308 controls the pressure drop across the filter segment 308, which in turn controls the draw resistance of the article 300. Therefore the selection of the material of the filter segment 308 is important in controlling the resistance to draw of the article 300. In addition, the filter segment 308 performs a filtration function in the article 300.

In one example, the filter segment 308 is made of a 8Y15 grade of filter tow material, which provides a filtration effect on the heated volatilised material, whilst also reducing the size of condensed aerosol droplets which result from the

heated volatilised material which consequentially reduces the irritation and throat impact of the heated volatilised material to satisfactory levels.

The presence of the filter segment 308 provides an insulating effect by providing further cooling to the heated volatilised components that exit the cooling segment 306. This further cooling effect reduces the contact temperature of the user's lips on the surface of the filter segment 308.

One or more flavours may be added to the filter segment 308 in the form of either direct injection of flavoured liquids into the filter segment 308 or by embedding or arranging one or more flavoured breakable capsules or other flavour carriers within the cellulose acetate tow of the filter segment 308.

In one example, the filter segment 308 is between 6 mm to 10 mm in length, more preferably 8 mm.

The mouth end segment 310 is an annular tube and is located around and defines an air gap within the mouth end segment 310. The air gap provides a chamber for heated volatilised components that flow from the filter segment 308. The mouth end segment 310 is hollow to provide a chamber for aerosol accumulation yet rigid enough to withstand axial compressive forces and bending moments that might arise during manufacture and whilst the article is in use during insertion into the device 100. In one example, the thickness of the wall of the mouth end segment 310 is approximately 0.29 mm.

In one example, the length of the mouth end segment 310 is between 6 mm to 10 mm and more preferably 8 mm. In one example, the thickness of the mouth end segment is 0.29 mm.

The mouth end segment 310 may be manufactured from a spirally wound paper tube which provides a hollow internal chamber yet maintains critical mechanical rigidity. Spirally wound paper tubes are able to meet the tight dimensional accuracy requirements of high-speed manufacturing processes with respect to tube length, outer diameter, roundness and straightness.

The mouth end segment 310 provides the function of preventing any liquid condensate that accumulates at the exit of the filter segment 308 from coming into direct contact with a user.

It should be appreciated that, in one example, the mouth end segment 310 and the cooling segment 306 may be formed of a single tube and the filter segment 308 is located within that tube separating the mouth end segment 310 and the cooling segment 306.

A ventilation region 316 is provided in the article 300 to enable air to flow into the interior of the article 300 from the exterior of the article 300. In one example the ventilation region 316 takes the form of one or more ventilation holes 316 formed through the outer layer of the article 300. The ventilation holes may be located in the cooling segment 306 to aid with the cooling of the article 300. In one example, the ventilation region 316 comprises one or more rows of holes, and preferably, each row of holes is arranged circumferentially around the article 300 in a cross-section that is substantially perpendicular to a longitudinal axis of the article 300.

In one example, there are between one to four rows of ventilation holes to provide ventilation for the article 300. Each row of ventilation holes may have between 12 to 36 ventilation holes 316. The ventilation holes 316 may, for example, be between 100 to 500 μm in diameter. In one example, an axial separation between rows of ventilation

holes 316 is between 0.25 mm and 0.75 mm, more preferably, an axial separation between rows of ventilation holes 316 is 0.5 mm.

In one example, the ventilation holes 316 are of uniform size. In another example, the ventilation holes 316 vary in size. The ventilation holes can be made using any suitable technique, for example, one or more of the following techniques: laser technology, mechanical perforation of the cooling segment 306 or pre-perforation of the cooling segment 306 before it is formed into the article 300. The ventilation holes 316 are positioned so as to provide effective cooling to the article 300.

In one example, the rows of ventilation holes 316 are located at least 11 mm from the proximal end 312 of the article, more preferably the ventilation holes are located between 17 mm and 20 mm from the proximal end 312 of the article 300. The location of the ventilation holes 316 is positioned such that user does not block the ventilation holes 316 when the article 300 is in use.

Advantageously, providing the rows of ventilation holes between 17 mm and 20 mm from the proximal end 312 of the article 300 enables the ventilation holes 316 to be located outside of the device 100, when the article 300 is fully inserted in the device 100, as can be seen in FIG. 1. By locating the ventilation holes outside of the apparatus, non-heated air is able to enter the article 300 through the ventilation holes from outside the device 100 to aid with the cooling of the article 300.

The length of the cooling segment 306 is such that the cooling segment 306 will be partially inserted into the device 100, when the article 300 is fully inserted into the device 100. The length of the cooling segment 306 provides a first function of providing a physical gap between the heater arrangement of the device 100 and the heat sensitive filter arrangement 308, and a second function of enabling the ventilation holes 316 to be located in the cooling segment, whilst also being located outside of the device 100, when the article 300 is fully inserted into the device 100. As can be seen from FIG. 1, the majority of the cooling element 306 is located within the device 100. However, there is a portion of the cooling element 306 that extends out of the device 100. It is in this portion of the cooling element 306 that extends out of the device 100 in which the ventilation holes 316 are located.

FIG. 11 shows a removable cover 400 for an aerosol generating device 100 as shown in FIGS. 1 to 8.

The removable cover 400 has an inner surface 402 which is configured such that, when the cover 400 is provided on the aerosol-generating device 100, the inner surface 402 contacts at least a portion of the housing 102 of the aerosol-generating device. In the example shown, in use the inner surface 402 contacts at least a portion of the front face 108, the rear face 110, the first side portion 112, and the second side portion 114 of the housing 102.

The inner surface 402 defines a volume 404 within which the aerosol-generating device 100 may be arranged in use.

The removable cover 400 has an opening 406 through which the aerosol-generating device 100 can be supplied to the volume 404 or removed from the volume 404.

The removable cover 400 has an outer surface 408 which is configured such that, when the cover 400 is provided on the aerosol-generating device 100, a user can touch the outer surface 408 of the removable cover 400 when interacting with the aerosol-generating device.

The removable cover 400 comprises a first aperture 410 arranged to correspond to the user interface 144 of the device 100. That is, when the device 100 is arranged within

the removable cover 400, the first aperture 410 is positioned around the user interface 144 such that the removable cover 400 does not cover the user interface 144 of the device 100.

The removable cover 400 comprises a second aperture 412 arranged to correspond to a socket/port for receiving a cable to charge a battery of the device 100. That is, when the device 100 is arranged within the removable cover 400, the second aperture 412 is positioned around the socket/port such that a power cable can pass through the second aperture 412 to the socket/port of the device 100.

The above embodiments are to be understood as illustrative examples of the invention. Further embodiments of the invention are envisaged. It is to be understood that any feature described in relation to any one embodiment may be used alone, or in combination with other features described, and may also be used in combination with one or more features of any other of the embodiments, or any combination of any other of the embodiments. Furthermore, equivalents and modifications not described above may also be employed without departing from the scope of the invention, which is defined in the accompanying claims.

The invention claimed is:

1. An aerosol-generating device for generating aerosol from an aerosol-generating material, the aerosol-generating device comprising:

a housing; and

a heating assembly arranged in the housing for receiving aerosol-generating material, the heating assembly being configured to heat aerosol-generating material received in the heating assembly,

wherein the housing has a characteristic extent in a first direction of not more than 85 mm, a characteristic extent in a second direction perpendicular to the first direction of not more than 45 mm, and a characteristic extent in a third direction perpendicular to the first and second directions of not more than 23 mm,

wherein the housing has a characteristic shape in the first plane, the characteristic shape being the same along at least 50% of the length of the housing in the first direction, and

wherein the characteristic shape is formed from an isosceles trapezoid having a height (h) of not more than 25 mm, a first base of the trapezoid being provided with a first convex portion extending along the entire first base, and a second base of the trapezoid being provided with a second convex portion extending along the entire second base.

2. The aerosol-generating device of claim 1, wherein the housing comprises a base which extends along a first plane normal to the first direction.

3. The aerosol-generating device of claim 2, wherein the housing comprises a top face arranged opposite to the base.

4. The aerosol-generating device of claim 3, wherein the top face extends along a fourth plane, the fourth plane extending along the third direction and forming a dihedral angle with the first plane of 2.5°.

5. The aerosol-generating device of claim 3, wherein the base and top face are connected by a body portion.

6. The aerosol-generating device of claim 5, wherein the body portion comprises a front face, rear face, first side portion, and second side portion, each extending from the base to the top face in the first direction, wherein the front face is arranged opposite the rear face, and the first side portion is arranged opposite the second side portion.

7. The aerosol-generating device of claim 6, wherein at least one of:

25

the front face and rear face are connected by the first side portion at a first edge of each face, and by the second side portion at a second edge of each face; the first side portion and/or the second side portion are substantially curved;

the front face and/or rear face is substantially planar; the front face, rear face, first side portion and second side portion are substantially perpendicular to the base; the aerosol-generating device comprising a user interface and/or indicator arranged in the front face of the housing;

a substantially curved edge connects the base and the body portion;

a substantially curved edge connects the top face and the body portion; or

the aerosol-generating device comprises a charging port provided in an aperture arranged in the first or second side portion.

8. The aerosol-generating device of claim 3, wherein the aerosol-generating device comprises a slidable cover arranged at the top face of the housing and configured to cover an opening of the heating assembly in a first position and not cover the opening in a second position.

9. The aerosol-generating device of 8, wherein the slidable cover has a thickness of 5 mm or less.

10. The aerosol-generating device of 1, wherein each convex portion is substantially semi-circular.

11. The aerosol-generating device of 10, wherein the radius (r_1) of the first convex portion is not more than 12 mm, and radius (r_2) of the second convex portion is not more than 11 mm.

12. The aerosol-generating device of claim 1, wherein the heating assembly at least one of comprises an induction heating unit or is operable in a plurality of modes.

26

13. The aerosol-generating device of claim 1, in combination with an aerosol-generating article.

14. A kit comprising the aerosol-generating device of claim 1, in combination with a removable cover for the aerosol-generating device.

15. A housing for an aerosol-generating device, the housing having a characteristic extent in a first direction of not more than 85 mm, a characteristic extent in a second direction perpendicular to the first direction of not more than 45 mm, and a characteristic extent in a third direction perpendicular to the first and second directions of not more than 23 mm;

wherein the housing has a characteristic shape in a first plane perpendicular to the first direction, the characteristic shape being formed from an isosceles trapezoid having a height (h) of not more than 25 mm, the first base of the trapezoid being provided with a first convex portion extending along the entire first base, and the second base of the trapezoid being provided with a second convex portion extending along the entire second base.

16. The housing according to claim 15, wherein the housing has a characteristic shape in a second plane perpendicular to the second direction, the characteristic shape being substantially right trapezoid with a height of not more than 45 mm.

17. The housing of claim 16, wherein at least one of the obtuse angle of the right trapezoid is less than 95°, or the corners of the shape in the second plane are rounded.

18. The housing of claim 15, wherein the housing has a characteristic shape in a third plane perpendicular to the third direction, the characteristic shape being substantially rectangular, wherein the corners of the shape in the third plane are rounded.

* * * * *
